PHASE MODULATION RECEIVER

Clarence W. Hansell, Port Jefferson, N. Y., assignor to Radio Corporation of America, a corporation of Delaware

Application January 18, 1939, Serial No. 251,473

6 Claims. (Cl. 250—20)

This invention involves phase modulation reception in a novel manner by a novel means. By this new means I avoid many of the difficulties which are met with in some of the phase modulation methods and receivers known in the past. In one known type of phase modulation receiver the carrier wave of the received signal is separated out by means of crystal filters or other highly selective circuits, increased in relative 5 amplitude, changed in phase by 90 degrees and reintroduced with the modulation side frequencies in a manner to convert a phase modulated wave into an amplitude modulated wave. Other known types of phase modulation receivers use 10 as a component part selective filters or circuits in various manners. In these known receivers the necessity of extremely accurate control of the carrier frequency is encountered, usually at an intermediate frequency following a first hetero- 15 dyne operation, in order that the carrier frequency may be held within the pass band of the crystal filters or highly selective circuits. Moreover, in some methods used in the past it has been found desirable to hold down the degree of 20 phase modulation at the transmitter to such an extent that second, third and higher order side frequencies may not become of appreciable amplitude. If the higher order side frequencies do 25 become appreciable in amplitude they cause harmonic distortion of the detected modulation, when the wave is converted to amplitude modulation and then rectified or detected.

My present invention involves conversion of phase modulation into frequency modulation, before final detection, in a superheterodyne type 30 of receiver having a final detector designed to modulate a frequency modulated wave. I convert a phase modulated wave into a frequency modulated wave, in the receiver, by means of 35 modulation frequency energy which is derived from the receiver circuits, after the frequency modulation detector, and fed back to frequency modulation detector a heterodyne or beating oscillator which is cooperating in the production of the frequency 40 modulated energy fed to the frequency modulation detector. The potentials fed back are modified in a manner such that the frequency of the beating oscillator is modulated unequally for the various modulating frequency energies. The 45 non-uniformity of potentials fed back is such as to result in conversion of the received phase modulated wave into intermediate frequency energy which is frequency modulated in a manner characteristic of the modulations on the phase 50 modulated wave being received.

To carry out my invention I may use an assemblage of parts already well known in the art for carrying out certain well known functions. It is, therefore, not believed to be necessary to describe each of these parts in detail for enabling 5 one skilled in the art to practice the invention.

In describing my invention reference will be made to the attached drawing wherein Figures 1 and 2 each show diagrammatically the essential elements comprised in two modifications of 10 my novel receiver. Other modifications will be apparent to those skilled in the art and for that reason, my invention is not to be considered to be limited except as defined in the claims.

One form of the invention is shown in Figure 15 1, in which I have illustrated diagrammatically a receiving antenna A or line L delivering energy characteristic of a phase modulated transmitted wave to the receiver. The received energy may be selectively amplified in amplifier 10 and is then 20 beat down to a lower intermediate frequency in a heterodyne detector or converter also in 10 by cooperating, or beating, of the received energy with energy derived from a heterodyne oscillator 12 included in the receiver.

The intermediate frequency energy is then selectively amplified in 14 and applied to a frequency modulation detector 16 of any known suitable type. I prefer a frequency modulation detector of the balanced, or push-pull type, which 30 treats corresponding side frequency energies, symmetrically located around the carrier frequency, equally in the detection process. The detector output, which contains modulation frequency energies corresponding to those applied 35 to the distant phase modulated transmitter, is then amplified in 18 and passed on to any desired utilization device such as a loudspeaker, telegraph line, tone keyer, recorder, repeater station, etc.

At some point after the frequency modulation detector a small portion of modulation frequency current is taken out through resistances 20 and passed through an inductance 22. The current will cause a voltage or alternating potential to 45 appear across the inductance 22 which has a value substantially proportional to the modulation potential at each frequency in the output of the frequency modulation detector multiplied by the modulation frequency. The alternating potential 50 developed across inductance 22 is utilized to cause a controllable frequency modulation of the first heterodyne oscillator 12. The amount of this modulation, or the frequency deviation of the oscillator, for any given modulation frequency 55

power in amplifier 18 is almost proportional to the modulation frequency and is given such polarity as to cause the degree of phase modulation of the carrier wave, at the intermediate frequency, to be reduced substantially in proportion to the inverse of the modulation frequency. As a result the phase modulated wave which would otherwise have been delivered to the frequency modulation detector is converted into a frequency modulated wave having a lower phase or frequency deviation than the phase or frequency modulation for each component frequency in the original phase modulation.

The overall result is that the frequency modulation detector 16 delivers an output which is substantially a correct reproduction of the original modulation input to the distant phase modulated transmitter. Thus I am able to use a frequency modulation detector to demodulate a phase modulated wave, without distorting the frequency characteristic of the modulation.

The modulation reducing arrangement of Figure 1 is useful in that it reduces the average strength of side frequency currents, as compared with carrier currents, and gives an equivalent exaltation of the carrier before detection. This is useful in reducing distortions brought about by selective fading which, as is well known, can cause over modulation of the carrier and distortion of the received modulation when the fading reduces the strength of the carrier to less than the peak value of the combined energies of the other frequency components present with the carrier. This process of carrier exaltation does not increase the effect of noise with respect to the signal because noise frequency components are reduced in the same proportion as the signal side band power. As a matter of fact the effect of noise is reduced of the carrier exaltation, as will be understood by those who have studied the advantages which result from exalting the carrier wave, with respect to the side band power, at the receiver.

In the arrangement of Figure 1, if the resistances 20 are connected directly to the frequency modulation detector output so that steady state unbalance in detector currents will be applied to the resistances 20 and if the inductance 22 also has resistance, or if resistance is used which becomes effective at zero and very low frequencies, it is possible to obtain automatic tuning or frequency control by varying the frequency of the first beating oscillator to keep the intermediate frequency always at almost the exactly correct value. That is, if 22 has sufficient resistance or resistance is inserted in this circuit a direct current potential may be developed therein which is a function of the mean frequency of the intermediate frequency, and this potential may be used to regulate the mean frequency of operation of the oscillator in 12 to hold the mean I. F. frequency substantially free of slow variations. Although it is usually preferable to derive the frequency control energy for automatic tuning from the frequency modulation detector vacuum tubes directly this is not necessary if the amplifier 18 is designed to act as a zero frequency or direct current amplifier as well as a modulation frequency amplifier. The automatic tuning feature will be rendered more effective if the resistances 20 are each shunted by an inductance which will pass direct currents freely, but which will pass only inconsequential amounts of modulation frequency currents.

It may be well to bring to attention the possi-

bilities for instability in the receiver of Fig. 2 brought about by reversal of phase of some frequencies fed back outside the normal useful frequency band. This instability may call for application of some of the inventions already known for eliminating such instability in inverse feed back circuits generally.

The receiver of Figure 2 is similar in effect to that shown in Figure 1 in that it converts a phase modulated wave into a frequency modulated wave before final detection. However, in the receiver of Figure 2, the potential for modulating the first beating oscillator is derived by the passing of modulating frequency currents resulting from demodulation through resistance 21 and capacity 23 in series. The alternating current component of potential across the capacity 23 is then used to frequency modulate the first beating oscillator 12 in a direction to increase the phase deviation of the modulated current in the output of the heterodyne first detector 19. This results in converting the original phase modulation into frequency modulation before final detection. At the highest modulation frequencies the increase in phase deviation at the intermediate frequency may be small, but the increase will become greater at lower and lower modulating frequencies within the useful range of modulating frequencies.

In the arrangement of Figure 2, it is desirable that direct current components of modulation be eliminated from the energy fed back to frequency modulate the first beating oscillator. This is accomplished by means of an alternating current transformer anywhere between the frequency modulation detector and the first beating oscillator. Direct current components are not passed on by the transformers which may be located as shown between 23 and the oscillator 12.

Of course, if desired, automatic frequency or tuning control may be utilized in the receiver of Figure 2 by deriving direct current potentials from the frequency modulation detector 16, or amplifier 18, and employing them with suitable polarity to control the average frequency of oscillator 12. Circuits for carrying this out have not been indicated in the diagram, but one skilled in the art can readily supply them.

Having thus described my invention, what I claim is:

1. In a system for demodulating phase modulated wave energy, a detector system normally responsive to frequency modulated waves, means for impressing phase modulated waves on said detector system, means for modifying modulation potentials derived from said detector system in accordance with their frequency, and means for modifying the phase modulations on said wave energy in accordance with said modified potentials.

2. A system as recited in claim 1 wherein said second named means is inductive in character and modifies said modulation potentials substantially in proportion to their frequency.

3. A system as recited in claim 1 wherein said second named means is capacitive in character and modifies said modulation potentials substantially inversely in accordance with their frequency.

4. The method of demodulating phase modulated wave energy which includes the steps of, beating said wave energy with oscillations to obtain wave energy of lower frequency, demodulating said wave energy of lower frequency to derive signal potentials which are not a true rep-

5 representation of the wave modulations, and modulating said oscillations by means of said potentials in a manner to cause said signal potentials to be a true representation of said wave modulations.

5. In a system for demodulating phase modulated wave energy, a demodulated system normally responsive to frequency modulated wave energy, phase modulated wave amplifying means
10 including an oscillation generator and a heterodyne detector, means for impressing said phase modulated wave energy and oscillations from said oscillation generator on said heterodyne detector, means for impressing the beat frequency output
15 of said heterodyne detector on said demodulation

system, means for modifying modulation frequency potentials derived from said demodulation system in accordance with their frequency, and means for modifying the wave length of the oscillations produced by said generator in accordance with said modified potentials to thereby modify the modulations on the beat frequency output of said heterodyne detector.

5. In a system as recited in claim 5 wherein means is included with said last named means to control the mean frequency of operation of said oscillation generator in accordance with slow changes in the mean frequency of said beat frequency output of said heterodyne detector.
